Primary Examiner — Catherine Ho*(74) Attorney, Agent, or Firm* — Nath, Goldberg & Meyer; Jerald L. Meyer; Morgan D. Rosenberg(57) **CLAIM**

The ornamental design for the combined display and vending machine as shown and described.

DESCRIPTION

FIG. 1 is a top front perspective view of a combined display and vending machine, showing my new design;

FIG. 2 is a front elevational view thereof;

FIG. 3 is a right side elevational view thereof;

FIG. 4 is a rear elevational view thereof;

FIG. 5 is a top rear perspective view thereof; and,

FIG. 6 is a top plan view thereof.

The dashed broken lines show portions of the combined display and vending machine that form no part of the claimed design. The combined display and vending machine is shown with two symbolic dot-dash break lines in its height. The appearance of any portion of the combined display and vending machine between the dot-dash break lines forms no part of the claimed design. Additionally, the dot-dash broken boundary lines define the bounds of the claimed design and form no part thereof.
